[57] CLAIM

The ornamental design for a watchstrap display stand,
substantially as shown and described.

DESCRIPTION

FIG. 1 is a side elevational view of a watchstrap display stand showing my new design, the other side views
being substantially identical thereto;

FIG. 2 is a front elevational view thereof;

FIG. 3 is a top plan view thereof;

FIG. 4 is a bottom plan view thereof;

FIG. 5 is a perspective view of a second embodiment of
the watchstrap display stand shown in FIG. 1;

FIG. 6 is a perspective view of a third embodiment of
the watchstrap display stand shown in FIG. 1; and

FIG. 7 is a perspective view of a fourth embodiment of
the watchstrap display stand shown in FIG. 1.

FIG. 3.

FIG. 1.

FIG. 2.

FIG. 4.

F I G. 5.

FIG. 6.

FIG. 7.
